UNITED STATES PATENT OFFICE

169,292

FORK OR SIMILAR ARTICLE

Joseph B. Stier, New York, N. Y.

Application October 11, 1952, Serial No. 21,799

Term of patent 3½ years

(Cl. D44—29)

To all whom it may concern:

Be it known that I, Joseph B. Stier, a citizen of the United States of America, residing in New York city, county of Kings, and State of New York, have invented a new, original, and ornamental Design for a Fork or Similar Article, of which the following is a specification, reference being had to the accompanying drawing, forming part thereof, wherein:

I claim:

The ornamental design for a fork or similar article, substantially as shown.

JOSEPH B. STIER.
